UNITED STATES PATENT OFFICE.

JAMES K. PIPER, OF WILMERDING, PENNSYLVANIA.

COTTON-PICKER.

No. 813,170.

Specification of Letters Patent.

Patented Feb. 20, 1906.

Application filed July 13, 1904. Serial No. 216,418.

To all whom it may concern:

Be it known that I, JAMES K. PIPER, a citizen of the United States of America, residing at Wilmerding, in the county of Allegheny and State of Pennsylvania, have invented certain new and useful Improvements in Cotton-Pickers, of which the following is a specification, reference being had therein to the accompanying drawings.

10 This invention relates to certain new and useful improvements in cotton-picking machines, and has for its object to construct a cotton-picker that will effectually pick and deposit the cotton from the open bolls into a 15 suitable receptacle and will perform the above operation without injuring the green bolls, blooms, or stalks of the cotton-plants.

20 A further object of the invention is to construct a cotton-picking machine that can be 25 readily and easily adjusted to conform to the height of the cotton-plants and that will be provided with a series of picker-fingers to engage the open bolls and remove the cotton therefrom and a novel construction to remove the cotton from the fingers and deposit same in the receptacle provided therefor.

25 The invention finally consists in the novel construction, combination, and arrangement of parts throughout to be hereinafter more 30 specifically described, and particularly pointed out in the claims.

35 In describing the invention in detail reference is had to the accompanying drawings, forming a part of this specification, and 40 wherein like characters of reference indicate similar parts throughout the several views, in which—

Figure 1 is a side elevation of my improved cotton-picking machine. Fig. 2 is a rear end 45 view of the same with the carriers, arms, and fingers removed. Fig. 3 is a top plan view of the frame, arms, and carriers, showing relative position of the fingers. Fig. 4 is a side elevation of one of the carriers, showing manner of attaching the fingers and also a portion 50 of the arms. Fig. 5 is a modification of the same. Fig. 6 is a side elevation of the rotary comb. Fig. 7 is a top plan view of the same. Fig. 8 is a side elevation of a modified form 55 of same. Fig. 9 is a perspective view of one of the lower carrier-arms. Fig. 10 is a similar view of one of the upper carrier-arms. Fig. 11 is a side elevation of one of the vertical shafts and fulcrum-disks. Fig. 12 is a side view of one of the fingers. Fig. 13 is an enlarged view of a portion of one of the fin-

gers. Fig. 14 is a transverse vertical sectional view of the same. Fig. 15 is a face view of the cog employed for lifting the arms of the carriers, showing same on the shaft. 60 Fig. 16 is an underneath view of the upper fulcrum-disk of the carrier-arms. Fig. 17 is a vertical longitudinal sectional view of the fulcrum-disk of the carrier-arms, showing pivotal point and a portion of the vertical 65 shaft. Fig. 18 is an underneath plan view of the lower plate of the carrier. Fig. 19 is a side elevation of the bevel-gear and worm-screw. Fig. 20 is a sectional view of a portion of the carrier, showing manner of securing 70 arms. Fig. 21 is a side view of a bevel-gear that may be employed in lieu of the worm-screw shown in Fig. 19. Fig. 22 is a sectional view of the end of the carriers. Fig. 23 is a side view of a portion of the toothed 75 rack, showing the spring employed for assisting the bevel-gear of the fingers into engagement with the rack. Fig. 24 is a plan view of the fulcrum of the carriers and arms. Fig. 25 is a vertical longitudinal section of a machine embodying my invention looking 80 toward one side from the center of the machine, the operating-gears being omitted. Fig. 26 is an edge view of the wheel employed for assisting in elevating the carrier-arms. 85 Fig. 26^a is a central transverse sectional view thereof. Fig. 27 is a detail view showing the means for elevating the lower carrier-arms onto their slide.

In the drawings, *a* represents the framework of the machine, consisting of the side rails and the front and rear upright standards. The drive-wheels *b b*, which are supported by axles secured to the framework, are each provided at the inner face of the hub 90 with a bevel gear-wheel *a'*, which is adapted to mesh with a bevel gear-wheel *a'*, secured on the horizontal shaft *a'*, said shaft being journaled in the frame at its rear end and at its forward end is journaled in the standard *a'*, secured on the side rail. At this end the horizontal shaft *a'* is provided with a worm-screw *a'*, which is adapted to mesh with a worm *b'*, secured on the vertical shaft *b'*, said shaft being also supported by the upper and lower side rails of the frame. The worm *b'* carries a bevel-gear *b''*, that meshes with a cog-wheel *b''*, carried on a shaft *b''*, journaled in a standard *b''''*, secured to the side rail, and the cog-wheel *b''* in turn meshes with a larger cog *b''''*, supported by an inclined shaft *c*, the lower end of said shaft being journaled in the 95 100

side rail and the shaft supported by and operating in a standard c' , secured on the side rail. The bevel-gear a' , besides meshing with the bevel-gear a' , also meshes with the bevel-gear c' , secured on the vertical comb-shaft c' , which is journaled in the lower and top rail of the frame, said comb-shaft being provided with arms c' , curved at their outer ends and forming the rotary comb to remove the cotton from the fingers. Near the upper end of the vertical shaft b' is rigidly secured a fulcrum-disk c' , and near the lower end of said shaft is secured a similar disk c' , each of which is composed of two sections, each section being provided with a bushing d for securing to the vertical shaft b' . These fulcrum-disks are formed with a circumferential groove d' near the outer periphery of the inner faces and a series of radial slots d' , extending each the same distance toward the center. The groove d' in the fulcrum-disk c' is adapted to receive pins d' , carried by arms d' and extending transversely therethrough near the lower end, and the fulcrum ends e of these arms d' are somewhat elliptical in shape, as at e' , (see Fig. 9,) and operate in the slots d' of the sections of the disks c' , the rounded ends e' of the arms d' permitting the downward inclination of the arms before arresting the movement thereof. These lower arms may be conveniently made from flat bars and are curved slightly or given a half-turn to bring the ends in the same plane, as is fully illustrated in Fig. 9 of the drawings, and are secured at their outer ends to the lower end of the carriers e' . These lower arms d' are provided on their upper faces with a series of cogs e' , arranged in segmental shape, adapted to engage in the cogs e' on the lower ends of the carriers e' , the said cogs e' being arranged at intervals at the ends of the carriers for the purpose of rocking the carriers, as will be more fully explained hereinafter. Each carrier e' is also provided on this end with a lug e' , which engages a lug e' on the end of the arm d' and turns the carrier one-quarter revolution when the cogs e' have passed from engagement with the cogs e' and will assist the carriers to their normal position. At the time the cogs e' have passed from engagement with the cogs e' the lug e' and lug e' engage to further turn the carrier to bring the same to its normal position for again being rocked by the cogs e' and e' . The upper arms d' have their inner ends pivotally secured to the disks c' in a manner similar to that for securing the inner ends of the lower arms d' to the disks c' and have their outer ends pivotally secured to the upper ends of the carriers e' in a manner similar to that in which the outer ends of the lower arms d' are secured to the lower ends of the carriers e' and are provided with a segmental toothed portion f , similar to the segmental portion e' of the lower arm, which is adapted to engage

with the cogs e' on the upper end of the carriers e' , and is also provided with a lug f' to engage the lug e' of the carrier and turn the same a quarter-revolution—that is, in the same manner and for the same purpose as described heretofore for the lower arm. 70

By referring to Fig. 4 of the drawings it will be observed that the arrangement of the lug f' upon the arm d' is such that it will engage the lug e' from a different position from that of the lug e' of the arm d' . By this arrangement the carrier is turned one-half revolution to bring the cogs of the carriers into engagement again with the segmental toothed portion of the arms for rocking the carriers. 75 This arrangement also prevents the carriers from turning freely. Both the upper and lower arms are secured to the carriers by a fulcrum-bearing f^2 , (see Fig. 17,) having a shaft portion f^3 , provided with an exterior annular groove f^4 , which receives a pin f^5 , passing through the end of the carrier and locking the fulcrum-bearing f^2 . The arms d' and d' are pivotally secured to this fulcrum-bearing. 80 On the carriers e' is secured a series of picker-fingers f^6 , provided with projecting points g , extending in longitudinal alignment with the fingers. These fingers f^6 are arranged at a slight incline and are provided with bevel gear-wheels g' , resting on washers or bushings g^2 , said wheels engaging in the toothed racks g^3 , said racks being curved and secured to the frame of the machine. In Fig. 5 I have shown friction-rollers g^4 , which may be employed in lieu of the bevel-gears g' , the cogs of the racks g^3 of course in this construction being dispensed with. 85

The front part of the machine is supported by braces g^5 , g^6 , in which is secured a vertical screw-threaded shaft h , operating at its lower end in the block h' , secured to the plate h^2 and provided on its upper end with a bevel gear-wheel h^3 , adapted to mesh with a gear-wheel h^4 , secured on the shaft, which is supported by a brace h^5 , fastened to the upper brace g^6 , said shaft being adapted to receive a crank which when turned will operate the vertical shaft h and adjust the forward end of the frame, as may be desired, either upward or downward. 90

The lower arms d' by reason of the half-turn in same will strike the inclined slide i , (see Fig. 1,) which is secured to the frame, with their flat portion, allowing the same to ride easily thereon, as will be more fully explained hereinafter, and each of the vertical shafts b' is provided on its upper end with bevel gear-wheels i' , meshing with bevel gear-wheels i^2 , secured on the ends of the shaft i^3 , which is supported by standards i^4 on the top of the frame, this arrangement transmitting motion to both sides should the mechanism on one side become broken or disarranged. 110

Within the frame at the front of the machine is provided an inverted-U-shaped flar- 115

ing sheeting or casing i^5 , with the smaller end toward the rear of the machine, forming a guide to carry the plants to the fingers. Arranged within the wheels b is an ordinary clutch-gear 11, having an operating-handle 10, employed for engaging and disengaging the bevel-gear a' and a^2 to impart motion to the mechanism and discontinue the same. This clutch-gear may be arranged with its operating-handle passing to a suitable point on the machine that will be convenient to operate the same. At the rear of the machine the frame portion is constructed with an upwardly-extending yoke k , which is of sufficient height to allow the arms to clear the same, said yoke being rigidly supported by braces $k' k'$, secured to the upright standards of the frame portion, this construction serving to rigidly support the frame. On the underneath side of the toothed racks g^3 , at the forward end of each, is secured a spring k^3 , (see Fig. 23,) having a downwardly-projecting tooth k^4 , which engages the bevel-gear g' and assists the same into an engagement with the teeth of the rack by turning the wheel into such a position that its teeth are ready to engage with the teeth of the rack. The ends of the carriers are provided with a hole k^5 , (see Fig. 17,) which is adapted to receive the shaft f^3 of the pivotal bearing f^2 . In Fig. 21, which is a modification, as before stated, of the gearing shown in Fig. 19, a gear-wheel l is employed to mesh with a bevel-gear l^x , that will be mounted on the shaft b^2 in lieu of the worm b' and screw a^5 , as shown and described throughout the specification. The wheel b^2 , secured on the shaft c , is provided on one side with a series of beveled teeth l' , which are adapted to engage the lower carrier-arms d^4 and assist the same on the slide i .

We will now assume that all the parts have been secured in their respective positions and the machine proper is in motion without the different parts being in operation.

The clutch is thrown in engagement, causing the bevel-gear a' to engage with the bevel-gear a^2 , and as the machine moves forward the shaft a^2 will be rotated, causing the worm-screw a^5 to engage in the worm-wheel b' and communicate motion to the vertical shafts b^2 , causing same to revolve and rotate the arms carrying the picker-finger carriers. As these carriers revolve the wheels $g' g'$ will engage in the toothed racks g^3 as they pass between the curved guides, (shown more especially in Fig. 25,) and this in turn communicates motion to the picker-fingers, causing the same to revolve simultaneously. The machine is drawn across the field with the same straddle of a row of plants, so as to bring the plants within the U-shaped casing i^5 , thus bringing the open bolls in direct contact with the picker-fingers, which engage in the said bolls and by reason of the projecting points wind the cotton on the fingers as they are revolved and carry the same around to the comb, the fingers of which, by reason of the incline in the picker-fingers, will engage the said picker-fingers at the rear, and as they continue to rotate and descend on their movement, keeping the picker-fingers and comb-fingers in contact until past engagement, the comb-fingers will thus be permitted to effectually strip the cotton from the picker-fingers and allow the cotton to fall into a suitable receptacle provided therefor.

During the time that the bevel gear-wheels g' are in engagement with the toothed racks g^3 the teeth e^2 of the lower arms, the teeth f of the upper arms will be in engagement with the teeth e^3 , serving to rock the carriers, the picker-fingers retaining an inclined position throughout the length of the cog-racks g^3 , their position being fully illustrated in Fig. 2 of the drawings by dotted lines. At the time that the bevel-wheels g' leave the racks g^3 the teeth e^2 and f of the upper and lower arms, respectively, have passed the point of contact with the teeth e^3 and the lug e^5 and f' of the arms come in engagement with the lugs e^4 of the carriers and operate the carriers, so as to throw the free ends of the picker-fingers toward the drive-shaft b^2 toward the front of the machine, which position they retain until the bevel gear-wheels of the fingers again come in contact with the racks, when they will be reversed to the former position to again engage the cotton by reason of the teeth being in engagement again. As the bevel-wheels on the picker-fingers are about to enter the toothed racks the spring k^3 engages the bevel gear-wheel before it reaches the teeth of the rack, compressing this spring, and as its tooth k^4 passes out of engagement with the bevel-gear g' the action of the spring in returning to its normal position rotates the picker-fingers and forces the bevel-wheel more readily into engagement with the teeth of the rack and prevents any lost motion at this point. As the bevel-gears $g' g'$ enter into engagement with the tooth-racks g^3 the picker-fingers will be revolved and will be entered into the bolls in an inclined position, thereby causing the projecting points g of the fingers to more readily engage the cotton and to effectively remove the same from the bolls.

As the teeth e^2 and f of the lower and upper arms, respectively, engage in the teeth e^3 in the end of the carriers the fingers will be in engagement with the cotton, and by the time the fingers have passed out of engagement the teeth will have passed the point of contact and the lugs e^5 and f' of the lower and upper arms, respectively, will engage the lug e^5 on the upper and lower end of the carriers and return the fingers to their original position. By this arrangement of inserting the fingers in the cotton-bolls at an inclined position and revolving the same therein, while

rotating in conjunction with the carriers, the same will engage the cotton much more effectively and remove the same from the boll with greater accuracy and neatness than is accomplished where the fingers enter the boll in a straight line, as it will be observed that the fingers will engage the cotton-boll throughout their entire path of travel.

The wheel b^3 is provided merely to assist in the elevating of the carrier-arms and guiding same onto the curved slide i . As the arms travel around in their endless course and the bevel-gears g' on the picker-fingers pass from engagement with the racks g'' the lower carrier-arms d^4 are engaged by the teeth l' and carried upward onto the slide i , at which time they pass from engagement with the said teeth l' of the gear b^5 .

It will also be observed that various changes may be made throughout in the details of construction without materially changing the same or departing from the general spirit of my invention.

Having thus described my invention, what I claim, and desire to secure by Letters Patent, is—

1. In a cotton-picker a frame, vertical shafts mounted in said frame, fulcrum-disks secured to said shafts near the upper and lower ends thereof, a series of arms fulcrumed in said disks, carriers mounted in the outer ends of said arms, a series of picker-fingers journaled in each of said carriers, means engaging said arms for moving the same vertically on their pivots during their endless travel, means for imparting motion to said vertical shafts to rotate the same and move the carriers in an endless course, a stationary means connected to the frame to engage said picker-fingers and revolve the same while passing through the cotton during the endless travel of the carrier, substantially as described.

2. In a cotton-picking machine, a frame, vertical shafts journaled in said frame, fulcrum-disks formed in two parts and secured to the said shafts, carrier-arms fulcrumed in said disks, carriers loosely connected to the outer ends of the arms, rotating picker-fingers journaled upon each of said carriers, means for moving the carrier-arms vertically upon their pivots to bring the picker-fingers into position to engage the cotton, gear-wheels mounted on each of said picker-fingers, combined with racks between which the picker-fingers pass and which engage the gear-wheels thereon to rotate the fingers while passing through the cotton, and means for driving said vertical shafts, substantially as described.

3. In a cotton-picker, a frame, vertical operating-shafts mounted therein, worm-gears on said shafts, disks secured to the said shafts, carrier-arms pivoted in the said disks, guides for controlling the said arms around their

pivots, carriers pivoted between the outer ends of the arms, picker-fingers journaled in the carriers at an inclination thereto and each finger provided with a wheel at its inner end to cause it to revolve, combined with racks between which the fingers are caused to pass, and which engage the wheels on the fingers to rotate the same, horizontal driving-shafts provided at one end with worm-gears to mesh with the worm-gears on the vertical shafts, the outer ends of the said arms being provided with teeth and a lug both of which are adapted to engage with teeth on the end of the carriers, substantially as described.

4. In a cotton-picker, a frame, supported upon wheels, beveled gear-wheels on the axles, horizontal shafts having gears, vertical shafts journaled in the frame, bevel-gears and combs secured to the vertical shafts, the gear-wheels on the axle meshing with the gears on the rear ends of the horizontal shafts, vertical driving-shafts having gears, the gear on the front ends of the horizontal shafts meshing with those on the lower ends of the vertical driving-shafts, combined with fulcrum-disks mounted upon said vertical driving-shafts, carrier-arms loosely connected at their ends to said fulcrum-disks, carriers loosely connected to the outer ends of said carrier-arms, means for moving said carrier-arms in vertical planes, separate means for rocking the carriers on their vertical axis, a series of picker-fingers journaled in said carriers, and means for rotating said picker-fingers during a part of the endless travel of the carrier-arms and carriers, substantially as described.

5. In a cotton-picker, a frame mounted on wheels, vertical shafts mounted in said frame, fulcrum-disks secured to said shafts near the upper and lower ends thereof, said shafts provided at their lower ends with gears, horizontal shafts provided with bevel-gears at their rear ends and worm-gears at their front ends adapted to mesh with the gears on the lower ends of the vertical shafts, combined with arms fulcrumed at their inner ends in said disks, means for moving said arms vertically, carriers pivotally connected to the outer ends of said arms, means for controlling the movement of the carriers during their travel, picker-fingers journaled in said carriers and provided with wheels at their inner ends, curved guides between which the fingers are moved, and vertical comb-shafts operated by the gears on the rear ends of the horizontal shafts and provided with combs for removing the cotton from the fingers, substantially as described.

6. In a cotton-picker the frame mounted on wheels, a rotary comb-shaft mounted therein, a vertical operating-shaft, disks secured to said shaft, carrier-arms fulcrumed at their inner ends in said disks and provided at their outer ends with segmental-shaped toothed

portions, means for moving said arms vertically, carriers pivoted between the ends of the arms and provided on their ends with teeth to engage the teeth on the arms, combined with picker-fingers journaled in the carriers and provided with operating-wheels at their inner ends, and curved racks between which the fingers are moved, to engage the wheels on the picker-fingers by which they are made to revolve, substantially as described.

7. In a cotton-picker, the frame mounted upon wheels, vertical shafts journaled in said frame and provided with gears near their lower ends, horizontal shafts supported by braces connected to the frame, and provided with gears to mesh with the gears upon the vertical drive-shafts, vertical shafts carrying combs and provided with bevel-gears which mesh with bevel-gears on the rear ends of the horizontal shafts, fulcrum-disks secured to the vertical drive-shafts at both their upper and lower ends, carrier-arms loosely attached to the disks, means for moving said arms vertically, carriers pivoted between the outer ends of the arms, means connected to the arms for rocking the carriers, a series of picker-fingers journaled upon each carrier, and provided with wheels near their inner ends and projecting picking-points which extend in a line along the fingers, and curved racks between which the fingers are moved to engage the wheels on the fingers by which they are caused to revolve while passing between the guides, substantially as described.

8. In a cotton-picker the frame mounted upon wheels, vertical operating-shafts journaled in said frame and provided with gears horizontal shafts journaled in the frame and provided with gears upon their forward ends to mesh with the gears upon the lower ends of the vertical shafts, fulcrum-disks secured to the vertical operating-shafts, carrier-arms loosely connected at their inner ends to the disks on the vertical shafts, means for moving said arms vertically, carriers pivotally secured between the ends of the arms, picker-fingers journaled in an inclined position in the carriers, and provided with wheels at their inner ends, guide-racks provided with teeth with which the wheels on the fingers engage as the fingers are moved between the guide-racks, the arms provided with teeth at their outer ends, and the carriers having teeth on their ends to engage the teeth on the arms, substantially as described.

9. In a cotton - picker, a frame mounted upon wheels and provided with side and upright rails, a screw-threaded vertical shaft threaded in the front of the frame, a bevel-gear on the upper end of the shaft, a brace secured to the frame, a bevel-gear and crank-shaft supported in said brace, a bearing-block supported horizontally above the front axle to receive the lower end of said screw-

threaded vertical shaft, a pair of vertical driving-shafts journaled in said frame, fulcrum-disks secured to the said shafts, a series of arms fulcrumed in said disks, carriers between the pivoted outer ends of said arms, a series of picker-fingers journaled in each of said carriers, means for moving said arms vertically on their pivots, means for operating said vertical drive-shafts, and means connected to the frame with which said picker-fingers are brought into engagement to rotate the same during the time they are in engagement with said means, substantially as described.

10. In a cotton-picker, the frame mounted upon wheels, vertical shafts journaled in said frame, combs mounted on said vertical shafts, vertical drive-shafts provided with gears at their lower ends, fulcrum-disks secured to said vertical shafts at their upper and lower ends, combined with arms loosely connected to said fulcrum-disks at their inner ends and provided with teeth and lugs at their outer ends, means for moving said arms vertically, carriers pivoted between the outer ends of the arms and provided on their ends with teeth and lugs which engage the teeth and lugs on the arms, a series of picker-fingers journaled in each carrier in an inclined position and provided with operating-wheels at their inner ends, the lugs on the arms being adapted to engage the lugs on the carriers when the teeth of the carriers and arms have passed from engagement to operate the carriers and throw the free ends of the fingers toward the vertical drive-shafts, and curved guides between which the fingers are moved for engagement of the wheels carried by the fingers with said guides to rotate the fingers, substantially as described.

11. In a cotton - picker, a frame, vertical shafts journaled in said frame, fulcrum-disks secured to the shafts at their upper and lower ends, carrier-arms loosely connected at their inner ends to said disks, and means for moving said arms vertically, combined with carriers pivoted between the outer ends of the arms, a series of picker-fingers journaled in each of said carriers and having projecting picking - points extending toward the free ends of the fingers, and means for causing the shafts to revolve and carry the carriers and picker - fingers around therewith, substantially as described.

12. In a cotton-picker, a series of carriers, a series of picker-fingers journaled in each of said carriers at an incline thereto and having projecting picking-points arranged in alignment theron, supporting-arms for the carriers, vertical operating-shafts, fulcrum-disks secured to said vertical shafts and in which said supporting-arms are loosely mounted, means for operating said supporting-arms vertically, said vertical shafts being provided with gears at their lower ends, combined with

horizontal shafts provided with worm-gears adapted to mesh with the gears on the vertical shafts, and revolving combs arranged on the rear end of the machine and operated by 5 said horizontal shafts, substantially as described.

13. In a cotton-picker, a series of carriers, a series of arms between which the carriers are mounted, vertical shafts to which the 10 arms are pivotally connected by horizontal pivots, and means for operating said arms vertically, combined with picker-fingers journaled in an inclined position in each of the carriers, and provided with projecting picking-points which are arranged in alinement thereon, means for turning the carriers on their axes, and means engaging the picking-fingers for causing the same to revolve while in engagement with the cotton, substantially 15 as described.

14. In a cotton-picker, the frame supported upon driving-wheels, the beveled gearing on the axle of said wheels, horizontal shafts journaled in the frame, and provided with 20 gears at their ends to engage the gears on the axle, and with worm-gears at their front ends, vertical shafts journaled in the frame, and provided with gears at their lower ends to engage the worm-gears on the front ends of the 25 horizontal shafts, combined with fulcrum-disks secured to the vertical shafts and provided with radial slots, arms fulcrumed at their inner ends to said disks, carriers pivotally supported between the outer ends of said 30 arms, means carried by said arms for rocking the carriers, a series of picker-fingers journaled in each carrier, means for revolving the fingers in unison with the rotation of the vertical shafts and carriers, a flaring U-shaped 35 casing for guiding the cotton to the fingers, and means for elevating the carriers and arms, substantially as described.

15. In a cotton-picker, a frame, vertical shafts journaled in said frame, fulcrum-disks 40 secured near the upper and lower ends of said vertical shafts and gears secured to their lower ends, horizontal shafts provided with gears on their front ends to engage the gears on the vertical shafts, and means for operating 45 said horizontal shafts, combined with carrier-arms, secured to the vertical shafts, means for operating said carrier-arms vertically, a series of carriers loosely connected to said carrier-arms, a series of picker-fingers 50 journaled in each of said carriers, each of said fingers having a wheel mounted thereon and provided with projecting points and curved racks between which the fingers are passed and which engage the wheels on the fingers 55 and which engage the wheels on the fingers 60 to rotate the latter, substantially as described.

16. In a cotton-picker, a frame mounted upon wheels, vertical shafts journaled in said frame and means for communicating motion to said shafts from the rear axle, combined

with fulcrum-disks secured to said vertical 65 shafts, a series of arms fulcrumed at their inner ends in said disks, carriers pivotally mounted between the outer ends of said arms, means for operating said arms vertically and means carried by the arms for rocking the 70 carriers, a series of picker-fingers journaled in each of said carriers and each of said fingers being provided with a wheel, and curved racks between which the fingers are passed and which engage said wheels for causing the 75 picker-fingers to rotate, substantially as described.

17. In a cotton-picker, the combination of a frame mounted upon wheels, vertical shafts mounted in said frame, means for rotating said 80 vertical shafts, fulcrum-disks secured to the vertical shafts near the upper and lower ends thereof, carrier-arms pivotally connected to said disks by horizontal pivots, carriers pivoted between the outer ends of said arms, 85 means for operating said carrier-arms vertically, and means carried by the arms for rocking said carriers, a series of picker-fingers journaled in an inclined position in each carrier and each finger provided with projecting 90 curved picker-points arranged in alinement and adapted to engage the cotton-bolls, means for causing said fingers to revolve while passing through the cotton, a screw-threaded vertically arranged shaft mounted upon the 95 front end of the frame for adjusting the height of the fingers, and a flaring U-shaped casing secured to the front end of the frame for guiding the cotton to the picker-fingers, substantially as described.

18. In a cotton-picking machine, a frame mounted on wheels, vertical shafts journaled in said frame, means for communicating a rotary motion to the shafts from the rear axle, disks secured to the shafts at their upper and lower ends, arms fulcrumed at their inner ends to the disks and provided at their outer ends with teeth and lugs, combined with carriers pivoted between the outer ends of the arms and provided with teeth upon both ends 110 to engage with the teeth upon the arms, a series of picker-fingers journaled in each carrier at an angle thereto and provided at their inner ends with wheels, racks adapted to engage said wheels to revolve the picker-fingers, 115 inclined sides secured to the frame and adapted to receive the arms to lift the same when the fingers are out of engagement with the cotton, combs mounted in the frame to remove the cotton from the picker-fingers, and 120 means for causing said combs to revolve, substantially as described.

In testimony whereof I affix my signature in the presence of two witnesses.

JAMES K. PIPER.
